UNITED STATES PATENT OFFICE.

GEORGE W. DIMMICK, OF BROOKLYN, NEW YORK, ASSIGNOR TO JAMES H. HART, LIMITED, OF SAME PLACE.

DESIGN FOR A SPOON.

SPECIFICATION forming part of Design No. 20,701, dated April 28, 1891.

Application filed March 30, 1891. Serial No. 387,083. Term of patent 3½ years.

To all whom it may concern:

Be it known that I, GEORGE W. DIMMICK, a citizen of the United States, residing in the city of Brooklyn, in the county of Kings, in 5 the State of New York, have invented and produced a new and original Design for Spoons and the Like, of which the following is a specification, reference being had to the accompanying illustrations, which constitute 10 a part thereof.

The figure shown in the accompanying photographic illustration represents a top plan view of a spoon, showing my design.

The leading figure of the design consists in 15 the representation within the cavity of the bowl a of the spoon of a perspective view of a portion of the city of Brooklyn, New York, which is known as "Brooklyn Heights," such representation being produced by any of the 20 well-known arts which are employed in the decoration of articles commonly composed of the precious metals, such as engraving, etching, die-stamping, &c. The handle b, which, like the bowl, may in its outline be of ordinary 25 configuration, has near its outer extremity a broad oval portion or thumb-rest b', upon or within which is represented the coat of arms of the city of Brooklyn, the same comprising the figure of a female in a sitting posture in the foreground and a partial view 30 of public buildings less distinctly represented in the background. The surface of the intermediate portion or shank *b*² of the spoon may receive suitable ornamentation consisting of raised foliations or scroll-work, with which 35 also the remaining portions of the upper surface of the handle of the spoon may be decorated, according to the taste or fancy of the artist.

The invention having been thus described, 40 what is claimed is—

The design for a spoon or the like herein shown and described, the same comprising the representation of Brooklyn Heights in the bowl of the spoon and the coat of arms 45 of the city of Brooklyn upon the broad oval portion of the handle of the spoon.

GEORGE W. DIMMICK.
